ARTICLE HOLDING AND EJECTING FIXTURE

Scott V. Smith, Danville, Ill., assignor, by mesne assignments, to Western Electric Company, Incorporated, New York, N. Y., a corporation of New York

Application August 20, 1948, Serial No. 45,387

9 Claims. (Cl. 209—81)

1

This invention relates to an article holding and ejecting fixture and more particularly to a fixture used in connection with a turret type electrical testing machine for holding the article in engagement with electrical contact members during the electrical testing of the article and for ejecting the article upon completion of the electrical testing thereof.

An object of the present invention is to provide an effective fixture for holding and ejecting articles.

In one embodiment of the invention, the fixture as used with a rotary turret type machine for electrically testing articles, forms a holder for receiving the article and guiding it for movement in one direction and the fixture has a spring-pressed plunger for ejecting the article from the holder, the plunger being movable by the article into a stressed or operative position and held there by a pivoted latch engaging the article and operable to release the article and cause its ejection. Electrical contact springs mounted on the fixture and actuated by the reciprocation of the ejection plunger are moved toward each other into engagement with terminals on the article when the article is moved into the holder, and the contact springs are spread apart by the plunger when the article is ejected from the holder.

Other objects and advantages will be apparent by reference to the following description and the accompanying drawings illustrating a preferred embodiment thereof in which

Fig. 1 is a plan view of a machine for electrically testing articles and employing the holding and ejecting fixtures forming the subject matter of the present invention;

Fig. 2 is a vertical longitudinal sectional view through the machine taken on the line 2—2 of Fig. 1;

Figs. 3 and 4 are views in perspective of the end construction of articles to be tested in this machine;

Fig. 5 is an enlarged plan view of the loading portion of the machine;

Fig. 6 is a detailed sectional view taken on the line 6—6 of Fig. 5 and showing a movable cam and the solenoid for actuating it;

Fig. 7 is a fragmentary vertical sectional view through a portion of the machine and the fixture taken on the line 7—7 of Fig. 5 and showing an article on the loading table in position to be moved into the fixture;

Fig. 8 is a fragmentary view of a portion of the apparatus shown in Fig. 7, showing the article

5 moved into an initial or inoperative position in said fixture and into engagement with the ejection plunger of the fixture;

Fig. 9 is a fragmentary vertical sectional view taken on the line 9—9 of Fig. 5 showing the pusher mechanism and an article moved by the pusher into its operative position in engagement with electrical contact springs on the fixture;

Fig. 10 is a fragmentary plan sectional view 10 of the drive for the pusher mechanism taken on the line 10—10 of Fig. 9;

Fig. 11 is a detailed vertical longitudinal sectional view through the vertically adjustable portion of the fixture showing the arrangement of 15 the two sets of contact springs and ejector members therein and an article in operative position relative to the lower set of contacts and ejector;

Fig. 12 is a vertical transverse sectional view 20 through the fixture taken on the line 12—12 of Fig. 11;

Figs. 13 and 14 are plan sectional views 25 through the fixture taken on the lines 13—13 and 14—14, respectively, showing a different type of article in operative position in each figure; and

Fig. 15 is an enlarged detailed view, partly in section, of one type of ejecting plunger.

The holding and ejecting fixture, constituting 30 the present invention, is shown in connection with a machine for electrically testing condensers or networks, which machine is disclosed and claimed in my co-pending applications, Serial Nos. 45,386, 45,385, filed August 20, 1948. This machine is designed to test various electrical characteristics

35 of networks or condensers which are enclosed in rectangular metal containers or cans 25 (Figs. 3 and 4), each of which is closed at its open end by a wall or closure 26 of insulating material apertured to accommodate the terminals 27 and, in some cases, the studs 28 extending there-

40 through. The metal containers 25 are of a pre-determined uniform length and width and their thickness varies according to the number of condensers and/or networks contained therein. The number of terminals varies, ranging from 2 to 4,

45 and the arrangement thereof likewise varies, depending upon the number of condensers or networks in the container. For purposes of convenience of description, the condenser and network unit and container therefor will hereinafter be referred to as an article 29.

Generally, the apparatus comprises a continually rotating turret or table 35 (Figs. 1 and 2) having a plurality of article holders 36 for receiving the articles 29 and carrying them through a predetermined circular path of less than one com-

plete revolution. Each of the articles is slid manually from a stationary loading table 38 into the holders 36 and into engagement with the end of a U-shaped ejecting plunger 39 stressed for movement outwardly by a spring 40 and guided for reciprocable movement in a vertically adjustable fixture 41, which is rotatable with the turret 35. In this initial or inoperative position 43 of the article 29 in the holder 36 (Figs. 1, 5 and 8), the terminals 27 are spaced from contact springs 46 stressed for vertical movement toward each other and spread apart in response to the outward or ejecting movement of the plunger 39 by a spreader cam 47 mounted thereon. As the article is carried along by the turret, it is engaged by a pusher mechanism 48 (Figs. 1, 5 and 9) and forced thereby radially inwardly to a second or operative position in the holder. In moving inwardly, the article imparts a movement radially inwardly to the plunger 39 to effect the closing movement of the contact spring 46 into engagement with the terminals 27 of the article. While the article is held in its forward or operative position by the pusher mechanism 48, a latch 50 associated with the holder 36 is actuated to engage the article and hold it in this position. As the turret 35 is rotated, the contacts 46 and the articles 29 associated therewith are carried through a plurality of testing stations and are electrically connected to a plurality of testing circuits and the articles are subjected sequentially to various electrical tests.

An article, when it is defective and cannot pass a test applied to it, is ejected at the end of that test by a cam 52, which actuates the latch 50 to release the article and permit the ejecting member 39 to eject the article radially outwardly from the holder and into a receiving chute 54. If the article passes the test applied thereto, a solenoid 56, associated with the operative testing circuit, is energized to move the cam 52 and render it inoperative and the article will continue its movement with the rotary table so that if the article is perfect or acceptable, it will be carried to an unloading station 60, where a stationary cam 62 (Fig. 1) actuates the latch to release the article and permit the plunger 39 to eject the article from the holder. At the unloading station, the articles are ejected radially onto a rotating turn table 64, which serves to move the articles out of the path of successive articles and permits the operator to slide them onto a stationary unloading table 65, from which they are later removed.

More specifically, the rotary table or turret 35 comprises an annular disc or supporting ring 70 (Figs. 1, 2, 5) positioned on top of a cylindrical drum portion 71 having an annular web or disc portion 72 provided at its inner periphery with a hub 73. The hub 73 is fixed to a sleeve 74 (Figs. 2 and 5) rotatably mounted on a stationary shaft 75, the sleeve 74 having a shoulder 76 engageable with the shoulder 77 on the shaft for supporting the sleeve 74 thereon. The shaft 75, at its lower end is secured in a supporting block 78 and, with the block 78, is fixed to a supporting base plate or platform 79. The reduced upper end of the shaft 75 is supported against movement by one end of a stabilizer arm or bracket 86 extending transversely from the upper end of a stabilizer column 87 which, at its lower end, is rigidly secured to the base 79.

Rotation is imparted to the turret 35 by a pair of belts 90 encircling the drum 71 and connected to a drive pulley 91 operatively connected to a

drive shaft 92 of a gear reducer 93. The gear reducer 93 is connected through a belt drive 94 to a motor 95, which, together with the reducer 93, is mounted on a bracket 99 extending from the post 87.

The article holders 36 (Figs. 1, 2, 5, 7, 8 and 9) on the rotary table 35 are formed by a plurality of elongated tapering blocks or members 106 secured to the upper surface of the supporting ring 70 and projecting radially outwardly from the outer peripheral edge thereof. The articles 29 are guided for radial movement and against lateral movement by the radially extending wall 107 on one side of the holder 36 and the portion 108 of the latch and the end of a pin 109 extending laterally from the blocks 106 and through apertures in the latches 50 on the other side of the holder. The outer upper edge of the supporting ring 70 between the spacer blocks 106 is inclined at 110 (Fig. 7) to facilitate the insertion of the article into the holder 36. A recess is formed in each of the blocks 106 to provide clearance for pivot shafts 112, to the upper ends of which one end of each of the latches 50 is secured. The outer ends of the latches 50 are bent at right angles to form shoulders or hooks 113, which are engageable with the ends of the articles 29 to hold them in their operative position in the holders. The shafts 112 are journaled in apertures extending through the plate 70 and drum 71 and each shaft has fixed to its lower end a cam follower comprising an arm 115 secured at one end to the shaft and at its other end rotatably supporting a roller 116. Compression springs 118, mounted in recesses in the blocks 106, urge the latches into closed position in engagement with the article.

The stationary cam 62, which actuates the latches 50 to their released or open position at the article unloading station 60, is formed on an annular member or cam ring 120 secured to the upper end of a dished annular supporting bracket 121 secured to the stationary shaft 75. The cam 62 has a surface 122 concentric with the axis of shaft 75, and which extends circumferentially from the discharge or unloading station 60 to a point adjacent the pusher mechanism 48 and serves to maintain the latches 50 in their open position while the holders 36 are in the loading zone and the articles are being loaded therein.

Adjacent the pusher mechanism 48, the cam surface 122 terminates and a roller 123 mounted on a bracket 124 in the path of the cam follower roller 116 serves to actuate the follower and move the latch 50 to its closed position, where it is effective to hold the article in its forward or operative position. The springs 118 act to retain the latches 50 in their closed position in engagement with the articles 29 and roller 116 of the cam follower and are positioned adjacent and substantially in engagement with an arcuate cam surface 125 concentric with the axis of the shaft, which surface 125 serves to limit the movement of the follower and the latch 50 when an article 29 is absent from the holder during the rotation of the table 35.

The cam ring 120 also serves as a support for the movable cams 52 (Figs. 5, 6 and 7) and the solenoid cam actuators 56. The movable cams 52, cylindrical in shape, are vertically movable in apertures formed in the cam ring 120 and are normally maintained in their upper or operative position in the path of movement of the cam follower rollers 116 by springs 127 and are withdrawn downwardly to their inoperative position

in response to the energization of the solenoids 56 associated therewith. Thus, the cams 52, which extend radially outwardly from the cam surface 125, act, when in operative position, to actuate the cam follower 116 and move the latch 50 to its open position to permit the ejection of the article from the holder 38. When the solenoid 56 is energized, it retracts the cam 52 to its inoperative position to render it ineffective to actuate the latches 50 as explained hereinbefore.

The pusher mechanism 48 (Figs. 1, 5, 9 and 10) for pushing the articles radially inwardly into their operative position in engagement with the contact members 46 and against the yielding pressure of the ejector 39 comprises a plurality of spaced pusher elements or rollers 129 rotatably mounted on a disc 130 fixed to the upper end of a shaft 131, which is rotatably journaled in a bearing member 132. The bearing 132 is formed in a mounting plate 133, which is mounted for sliding movement on a supporting plate 134 secured to a pair of spaced supporting brackets 135 extending from and fastened to the stationary support 121. The plate 133 is guided for limited radial movement by a pair of shouldered studs 137 positioned in radially extending guide slots 138 in the supporting plate 134. A sprocket 142, pinned to the shaft 131, is connected by a sprocket chain 143 to a sprocket 144, which, in turn, is keyed to a shaft 145 rotatably mounted in a bearing 146 formed on the supporting plate 134. A disc 147, keyed to the upper end of the shaft 145, has a plurality of equally spaced radially disposed slots 148, which are engageable by drive pins 149 extending downwardly in spaced relation to each other from the underneath surface of the annular plate 70 of the rotary table 35. Thus, the pins 149, moving with the rotatable table 35, engage in the slots 148 of the disc 147 and impart rotation thereto which, in turn, through the chain drive, imparts rotation to the disc 130 and pusher rollers 129. The pusher elements or rollers 129, being spaced equiangularly about and equidistant from the axis of the rotation of the disc 130, engage successive articles and move them radially inwardly on the rotatable table from their outer or inoperative position to their inner or operative position against the yielding pressure of the ejecting members 39 to effect the engagement of the terminals 27 with the electrical contact members 46.

The fixtures 41 (Figs. 5, 7, 8, 9 and 11 to 15), in which the contact members 46 and the ejector members 39 are mounted, comprise elongated tapering units nested together in annular form and secured to an annular disc or supporting plate 160 by screws 161 (Fig. 5) fitting in aligned vertical grooves in the diverging side walls of the adjacent fixture units. Each fixture 41 is associated and radially aligned with an article holder 36 and contains two sets of contact members 46 and ejector members 39 arranged at two levels, one set in superposed relation to the other. One set of contacts 46 and ejector 39, as, for example, the upper one, is adapted to accommodate articles having studs 28, as disclosed in Fig. 3, and the other or lower set of contacts and ejector is adapted to be used for testing articles having end constructions as disclosed in Fig. 4.

The supporting plate 160 and the fixtures 41 are vertically adjustable to align horizontally the upper or lower sets of contacts and ejectors with the holders 38 and also to adjust the position of the contacts and the ejectors of each set ver-

tically relative to the holders when used in testing articles of different thicknesses. A plurality of rods 163, fixed at one end to the plate 160, extend downwardly through apertures in the web or disc portion 72 of the turret 35 and are secured at their lower ends to an annular plate 164, the plate 164 resting on an anti-friction thrust bearing 166 slidably mounted for vertical movement on the sleeve 74 and supported by a plurality of thrust pins 167. The pins 167 extend upwardly from an internally threaded nut 168 mounted in threaded engagement with an externally threaded sleeve 170, which, in turn, is mounted for rotation on the stationary shaft 75 and is actuated through a worm drive under control of an operating handle 175. Thus, by turning the handle 175, the fixtures 41 may be adjusted vertically to align either set of contacts 46 and ejectors 39 horizontally relative to the articles 29 in the holders.

Each fixture 41 comprises a housing formed in three sections secured in superposed relation by screws 183 and having upper intermediate and lower horizontal wall portions 184—185 and 186, respectively, and side walls 188—188. In each of the upper and lower compartments formed by the housing is positioned one set of contacts and ejector members. Guideways or slots 190 are formed in the side walls 188 for supporting the ejector members 39 for horizontal reciprocable movement and recesses 191 are provided in the fixture for receiving a plurality of blocks of insulation 193 to form a wall for supporting the contact springs 46. The ejecting plungers 39 are U-shaped and, as previously described, are normally urged radially outwardly by compression springs 40 interposed between the plunger 39 and the wall 193 and movement outwardly of the ejector is limited by pins 196 engageable with the ends of slots 197—197 formed in the side walls 188 of the fixture. The parallel spaced leg portions 199 of the U-shaped ejector plunger 39 are provided at their outer ends with seats 200 adapted to be engaged by portions of the article 29.

In the lower set of ejectors (Fig. 4), the seats 200 are formed on the outer ends of the leg portions 199 and have angularly disposed guide surfaces 201 extending outwardly therefrom and are adapted to be engaged by the end portion of the article which is positioned laterally on the seats by the inclined portions 201. In the upper set of ejectors 39 (Figs. 13 and 15), the seats 200, formed by the notches in the leg portions 199, are spaced from the ends of the plunger and are adapted to receive the studs 28 projecting from the article 29 of the type of construction shown in Fig. 3. The outer ends of the leg portions 199 are provided with inwardly directed inclined surfaces 202, which aid in guiding the studs 28 of the article into position on the seats 200.

To insure a positive contact between each of the studs 28 of the article and the plunger 39, in order to electrically ground each stud to the machine, one of the seats of the plunger is provided with a mechanism to compensate for a slight difference in length between the studs 28 of the article. The shoulder 203, forming one of the seats, is positioned a greater distance from the end of the ejector plunger 39 than the other seat and a movable abutment member, in the form of a ball 204, is mounted in a bore 205 in the leg 199 of the plunger and normally projects beyond the shoulder 203. The abutment member 204, which is retained in the bore 205 by the 75 converging side walls at the end of the bore, is

urged outwardly by a spring 206, which is held compressed by a plug 207 retained in the bore 205 by the pin 196. Thus, when an article having studs 28 of slightly different lengths is moved into engagement with the seats of the plunger 39, one stud 28 will abut the regular seat 200 and the other stud 28, whether the short or long one of the two, will be engaged by the self-adjusting abutment member 204 associated with the other seat.

The cam or contact spreader member 47 is fastened to the intermediate portion of the U-shaped ejector 39 by a screw 209, the end of which projects beyond the ejector, and serves as a guide pin for the compression spring 40. The contact members 46, four in number for each set, are in the form of elongated flat spring members disposed on opposite sides of the plunger 39 and have inwardly directed end portions 210 engageable with the terminals 27 of the article 29. Rigidly supported at one end in the block 193, the contact members 46 are flexed for movement toward each other transversely to the direction of movement of the ejector member 42 and the article 29. Intermediate their ends, the contact members 46 are provided with inclined offset or cam portions 211 engageable with the inclined portions of the cam members 47, and which portions 211 cooperate with the cam 47 to move the contacts 46 in a substantially vertical direction away from each other to a spread or open position, in response to the horizontal movement of the ejector outwardly to its normal extended position.

In response to the inward movement of the ejector 39, the cam member 47 will disengage itself from the contacts 46 and permit the contacts to move toward each other to a closed position in engagement with the terminals 27 on the article. Thus, when an article 29 positioned in the holder 36 on the turret 35 is moved horizontally from an inoperative position to an operative position by the pusher mechanism 48, it moves the ejector plunger 39 radially inwardly from its normal extended position to its operative position and causes the contact springs 46 to move towards each other into engagement with the terminals 27, which are subsequently sequentially electrically connected through the contacts to the various testing circuits. The inward movement of the ejector 39 also further compresses the compression spring 40 so that, upon disengagement of the latch 50 from the article 29, the ejector 39 is moved outwardly with a sudden or snap action to eject the article from the holder 36 and the turret 35 and simultaneously therewith move the contact springs 46 to their open position.

Correspondingly positioned spring contacts in each pair of superposed sets of contacts 46 are electrically connected together by a conductor 214 and by conductors 215 they are connected to brushes 216 mounted in a cylindrical shoulder holder 217 which, in turn, is secured to the rotary sleeve 74 for rotation therewith. The brushes 216 are adapted to engage sequentially a plurality of stationary commutator segments 219 suitably supported and connected by conductors 223 to various testing circuits (not shown) for applying various electrical tests to the articles.

As they are carried along by the turret 35, the articles 29 pass through a plurality of testing stations and are connected successively and for predetermined periods of time to the various testing apparatus and are subjected to the vari-

ous electrical tests to determine whether the values of certain electrical characteristics of the article fall within or outside of an acceptable range. In each test station, at a point where the article nears the end of its movement therein, there is located one of the cams 52 and a solenoid 56, which is electrically connected into the testing circuit associated with the station. If the value of the electrical characteristic of the article being tested falls within the set minimum-maximum range of the test circuit applying the test, the solenoid 56 is energized to withdraw the cam 52 and render it inoperative and the latch 50 holding the article in its operative position in the holder is not actuated at this point to release the article. If the value of the characteristic of the article being tested falls below the minimum or above the maximum range of the setting of the testing apparatus testing the article, the solenoid 56 remains deenergized and the cam 52 remains in its normal operative position and engages the cam follower 116 to actuate the latch 50 and disengage it from the article, thus releasing the article and causing its ejection from the holder 36. Tubular chutes 54, arranged to receive the articles ejected at the various test stations, guide the articles 29 into suitable receptacles or bins (not shown). The rejected or imperfect articles are thus sorted into groups according to their defects and the good or acceptable articles are carried by the turret 35 to the unloading station 60, where, as previously mentioned, the stationary cam 62 actuates the latches to release the articles 29, which are thereby ejected onto the rotating turn table 64.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. A fixture for holding articles during the electrical testing thereof comprising a supporting means, a holder on said supporting means for supporting an article to be tested and for guiding said article for reciprocable movement, an ejector slidably mounted on said supporting means for movement in a direction parallel to the reciprocable movement of said article, contact members mounted on said supporting means on opposite sides of said ejector and stressed for movement to a closed position and engageable in said closed position with terminals on said article, cam elements on said ejector engageable with said contact members, spring means for stressing said ejector in one direction to eject an article from said holder and to cause the camming of said contact members to open position, said ejector being movable in the opposite direction by the movement of said article to a predetermined operative position to effect a movement of the contact members to a closed position in engagement with the terminals on said article, a latch member for holding said article in its operative position, and means for releasing said latch from said article to cause the ejection of said article from said holder.

2. A fixture for holding articles during the electrical testing thereof comprising a supporting means, a holder on said supporting means for supporting an article to be tested and for guiding said article for reciprocable movement, an ejector

slidably mounted on said supporting means for movement in a direction parallel to the reciprocable movement of said article, contact members mounted on said supporting means on opposite sides of said ejector and stressed for movement to a closed position and engageable in said closed position with terminals on said article, cooperating cam elements on said ejector and said contact members, spring means for stressing said ejector in one direction to eject an article from said holder and to cause the camming of said contact members to open position, said ejector being movable in the opposite direction by the movement of said article to a predetermined operative position to effect a movement of the contact members to a closed position in engagement with the terminals on said article, a pivoted latch member engageable with the end of said article for holding said article in its operative position, cam follower means operable to actuate said latch member, a cam for actuating said cam follower means, and means for effecting relative movement between said supporting means and said cam.

3. A fixture for holding articles during the electrical testing thereof comprising a pair of supporting members, a holder on one of said supporting members for supporting articles of different heights to be tested and for guiding said articles for reciprocable movement, contact members mounted on the other of said supporting members biased for movement to a closed position and engageable in said closed position with terminals on said articles, an ejector plunger slidably mounted on the other of said supporting members for movement in a direction parallel to the reciprocable movement of said articles, cooperating cam elements on said ejector and said contact members, spring means for stressing said ejector in one direction to eject an article from said holder and to cause the camming of said contact members to open position, said ejector being movable in the opposite direction by the movement of said article to a predetermined operative position to effect a movement of the contact members to a closed position in engagement with the terminals on said article, means for raising and lowering the position of one of said supporting members relative to the other to align the contact members with respect to the terminals on the articles to be tested, a latch member for holding said article in its operative position, and means for releasing said latch from said article to cause the ejection of said article from said holder.

4. A fixture for holding an article having terminals and attaching studs extending from one end thereof comprising a supporting means, a holder on said supporting means for supporting an article to be tested and for guiding said article for reciprocable movement, a metal plunger mounted on said supporting means for reciprocable movement and having a pair of seats engageable with the studs of articles to be tested to establish an electrical ground connection therewith, one of said seats including a movable abutment member yieldably mounted on said plunger for limited movement relative thereto in the direction of movement of said article, said plunger being movable in one direction in response to a predetermined movement in said direction of said article, resilient means for moving said plunger in the opposite direction to eject said article from said supporting means, contact members carried by said supporting means and

stressed for movement from an open to a closed position and engageable in said closed position with terminals on said article, cooperating cam elements on said plunger and contact members for moving said contact members to open position in response to movement of said plunger in said opposite direction to eject said article, a latch member for holding said article in its operative position, and means for releasing said latch from said article to cause the ejection of said article from said holder.

5. A fixture for holding articles during the electrical testing thereof comprising a supporting means, a holder on said supporting means for supporting an article to be tested and for guiding said article for reciprocable movement, a U-shaped plunger mounted for reciprocable movement in said supporting means and having outwardly directed spaced end portions engageable with the article to be tested and on opposite sides of said terminals thereof, said plunger being movable in one direction in response to a predetermined movement in said one direction of said article, contact springs mounted in said supporting means on opposite sides of the U-shaped plunger and between the spaced end portions thereof, said contact springs being biased to move towards each other to a closed position and being engageable in said closed position with the terminals on said article, cooperating cam elements on said plunger and said spring contacts operable to move said contacts away from each other to an open position in response to movement of said plunger, a spring for moving said plunger in the opposite direction to eject an article from the holder and to effect the movement of said contact spring to an open position, a movable member engageable with the end of said article to hold said article against ejection, and an actuator operable to disengage said movable member from said article and cause its ejection from said holder.

6. A fixture for holding articles during the electrical testing thereof comprising a supporting means, a holder on said supporting means for supporting an article to be tested and for guiding said article for reciprocable movement, contact members mounted on said supporting means and stressed for movement to a closed position and engageable in said closed position with terminals on said article, a plunger mounted on said supporting means in the path of movement of said article and movable in one direction by a predetermined movement of said article to effect the movement of said contact members to closed position in engagement with the terminals on said article, spring means for moving said plunger in the opposite direction to move said contacts to open position and to eject said article, a latch for holding the article against movement in said opposite direction, and a member for tripping said latch to release said article and cause its ejection.

7. A fixture for holding articles during the electrical testing thereof comprising supporting means, contact members carried by said supporting means and stressed for movement from an open to a closed position and engageable in said closed position with terminals on said article, a plunger mounted on said supporting means for reciprocatory movement and engageable with said article and movable thereby in one direction, resilient means for moving said plunger in the opposite direction, cam means on said plunger engageable with said contact members for moving

said contact members to open position in response to movement in said opposite direction of said plunger, guide means on said supporting means for supporting and guiding said article for movement toward and away from said contact members, whereby said article may be moved on said guide means to an operative position to said plunger and effect the engagement of the contact member with the terminals on said article, latch means for holding said article in operative position, and means for disengaging said latch means from said article to permit the plunger to eject said article from said supporting means.

8. A fixture for holding articles during the electrical testing thereof comprising supporting means, a holder on said supporting means for holding an article being tested and for guiding said article for reciprocable movement, contact members mounted on said supporting means for movement transversely to the reciprocable movement of said article and engageable with terminals on said article, an ejector slidably mounted on said supporting means for movement in a direction parallel to the reciprocable movement of said article, resilient means for urging said ejector in one direction to eject an article from said holder, cam elements on said ejector for moving said contact members transversely to the movement of said ejector to an open position in response to the movement of said ejector in said one direction, said ejector being movable in an opposite direction by the movement of said article to a predetermined operative position,

means for moving said contact members to a closed position in engagement with the terminals on said article in response to the movement in said opposite direction of said ejector, a pivoted latch member engageable with the end of said article for holding said article in its operative position, cam follower means operable to actuate said latch member, a cam for actuating said cam follower means, and means for effecting relative movement between said supporting means and said cam.

9. A fixture for holding articles during the electrical testing thereof comprising spring pressed contacts for engaging terminals on an article, a plunger for moving said contacts to inoperative position, resilient means for actuating said plunger, a locking device associated with said fixture for holding an article in the fixture against the action of the plunger, a tripping mechanism for tripping said locking device, including cam means, and means for disabling said cam means.
